CLAIM

The ornamental design for an adjustable guitar nut, as shown and described.

DESCRIPTION

FIG. 1 is a front, right and top perspective view of an adjustable guitar nut, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a hole; and,

FIG. 10 is an exploded view thereof.

The broken lines shown in the drawings are included for the purpose of illustrating portions of the adjustable guitar nut that form no part of the claimed design.
